HAIR CURLER

Della M. Mally, Gibson City, Ill.

Application July 12, 1955, Serial No. 36,927

Term of patent 14 years

(Cl. D86—10)

FIG. 2

Fig. 1 is a front perspective view of the hair curler showing my new design; and

Fig. 2 is a top plan view of the hair curler drawn to a reduced scale.

I claim:

The ornamental design for a hair curler, substantially as shown and described.
